RIBBED FRUSTO-CONICAL LINING FOR TUBE MILLS

Paul Louis Fobelets, Boitsfort, Belgium, assignor to Societe Anonyme Usines Emile Henricot, Etienne, Belgium, a company of Belgium

Application October 10, 1955, Serial No. 539,547

Claims priority, application Germany October 23, 1954

6 Claims. (Cl. 241—183)

This invention relates to cylindrical grinding mills of the kind in which the material to be ground travels from a supply point arranged at one end thereof to a discharge point, where it leaves the mill in the ground state.

Such tube mills which are used for widely differing purposes, especially for the grinding of cement, are interiorly lined with hardened steel plates provided with projections which grip the material as well as the grinding bodies upon rotation of the mill thereby raising them to a certain extent whereupon they fall down and by impact and friction disintegrate the material to be ground.

Originally the interior of such mills was made continuously cylindrical. Later it was found that from the point of view of efficiency it is advantageous to subdivide the mill into a plurality of subsequent sections and to use in these sections grinding bodies the size of which gradually diminishes in consecutive sections in the direction of travel of the material.

In order to ensure that the grinding bodies remain in their respective sections, the sections are usually separated by walls arranged perpendicular to the axis of the mill with orifices allowing only the ground material to pass therethrough.

The number of walls required in these types of mills increases the weight and costs considerably. Moreover the walls are subject to wear, necessitating frequent renewal of them. Further frequent regrading of the grinding bodies in the various sections is required, since they wear out quickly and lose their prescribed dimensions.

With the aim to avoid these disadvantages, it has later been proposed to subdivide the mill into sections not by intermediate walls, but by making each section frustoconical in shape narrowing in the direction of travel of the material to be ground so that a number of subsequent converging surfaces are formed, separated one from the other by steep radial steps.

By this construction the grinding bodies are retained in their proper sections and the premature movement of the material to a subsequent section is prevented, but only so long as the grain size is relatively small sand-like or less than about $\frac{1}{8}$ inch size. A material of coarser grain size however behaves like grinding bodies of equal weight. Consequently the larger constituents of the material to be ground, having a lower density than the grinding bodies, proceed into sections of the mill containing grinding bodies too small to exert a sufficient impact on elements of this size.

According to a further proposition these disadvantages are at least partially avoided by forming the frustoconical surfaces not as plain surfaces or surfaces corrugated in transverse direction, but of a plurality of projections, the heads of which follow the general frustoconical formation of the section. By this arrangement of the projections the distances being sufficiently small to prevent the grinding bodies from becoming jammed between them, the coarser grains of the material are

2

retarded and thereby prevented to migrate to following sections before being sufficiently disintegrated.

The projections raise the material to be ground together with the grinding bodies without any relative movement taking place between the grinding bodies and the lining during this lifting. That means that any sliding of the material to be ground on the grinding surface and consequently the unnecessary expenditure of power for a repeated raising of the material is obviated. Moreover by raising the grinding bodies to a higher level their impact on the material becomes more efficient.

This however offers the disadvantage that due to friction from the projections the return of the grinding bodies to the lowest point of the frusto-conical sections does not take place quickly enough, which could be detrimental to the output of such mills.

By the present invention all the disadvantages of the known constructions of tube mills are avoided without introducing new drawbacks whilst simultaneously increasing the output of the mill and reducing wear.

According to the invention the grinding surface of the lining of the frusto-conical zones formed of a plurality of plates of hardened steel is constituted by longitudinal ribs of cam-like profile, separated from one another by longitudinal grooves of a width not allowing grinding bodies to penetrate into them, adjacent parts of the surfaces of each two longitudinal ribs being so inclined with respect to one another as to form runways for the grinding bodies leading towards the lowest point of the frusto-conical section. Preferably these runways are interrupted by transverse grooves subdividing the ribs in distances greater than the width of the ribs.

By this construction the considerable lift exerted on the material to be ground and the grinding bodies by the rotation of the mills is maintained, and at the same time the return movement of the grinding bodies is accelerated. The subdivision of the ribs by transverse grooves at comparatively large intervals prevents the propagation of undesirable deformations due to the impact of the grinding bodies into neighboured areas of the lining plate and improves the cold working by the impact of the grinding bodies on the relatively big grinding surface consisting of the total area of the individual parts isolated from one another by the grooves.

On the crossing point of the transverse grooves with the longitudinal grooves local enlargements are formed, wherein, due to small grinding bodies or larger bits of material in the process penetrating and becoming jammed into them, obstructions are formed which exert on the material a retarding effect which may be desirable in certain circumstances.

According to a particular feature of the invention the surface of the ribs in the neighborhood of the longitudinal grooves is flat so that between these faces and the adjacent grooves edges are formed. By this arrangement the lifting effect of the runways formed by opposite areas of adjacent ribs is no longer dependent on the diameters of the grinding bodies. The top surfaces of the ribs are however preferably slightly cambered.

The depth of the longitudinal and preferably also of the transverse grooves should be relatively considerable and preferably larger than half the width of a rib, in order to secure sufficient separation of the ribs from one another, and to prevent any penetration of the grinding bodies down to the bottom of the grooves. The grooves can taper slightly inward from the top to the bottom.

The transverse grooves of neighbouring ribs are preferably arranged offset to one another so that a T-shape arrangement results at their crossing with the longitudinal grooves.

According to a further feature of the invention the ribs are reinforced in their area between the transverse

grooves opposite to a transverse groove of the adjacent rib. The object of these reinforcements is to obtain a snake-like movement of the grinding bodies rolling down and also to retard jamming of the grinding bodies when they become smaller owing to wear.

According to a further feature of the invention it has also been found advantageous for an even distribution of the grinding bodies to block alternate or all of the longitudinal grooves just before the end of the frusto-conical section is reached, and by this arrangement to stop the grinding bodies just clear of the bottom.

Further features and details of the invention will become clear from the following description of a cylindrical grinding mill provided with a lining according to the invention, given by way of example, with reference to the accompanying drawings, in which:

Figure 1 is a longitudinal section of a mill constructed according to the invention;

Figure 2 is a plan view of a lining plate, that is, a developed projection thereof in a horizontal plane tangent to the mill shell cylinder;

Figure 3 is a section along the line III—III of Figure 2 in which the direction arrows (line of sight) lie in the plane of the liner plate, that is, the section is perpendicular to the plane of Figure 2;

Figure 4 is a section along the line IV—IV of Figure 2.

The tube mill illustrated in Figure 1 is in general of cylindrical shape. The material to be ground is fed in at one end 2, which in the figure is on the left hand side and discharged at the opposite end at 3. The shell 4 of the mill encloses the consecutive sections 5', 5", 5''' formed of a plurality of liner plates 8 which internally are made frusto-conical in shape. In the longitudinal direction the total of the sections thus formed results in a succession of inclined steps, in each of which the part lying towards the discharge end lies nearer to the axis of the mill than that lying towards the supply end, whereby a radial shoulder is formed between every two consecutive sections. One of the plates 8 from which the linings of the sections are composed which have dimensions of, for example, 500 x 250 millimetres is shown in detail in Figures 2 to 4. The plates present the substantially continuous ribs 7', 7", 7''' separated by the longitudinal grooves 6', 6", 6''' . . . The apparent convergence or taper of the plate 8 and the longitudinal grooves 6', 6", and 6''' in Figure 2 is due to the planar projection of the curved inclined surface of the plate, that is, the development of the surface on a horizontal plane tangent to the mill shell cylinder. Actually, the plate is rectangular in outline and the longitudinal grooves are parallel to one another, the plan projection providing an illusion of convergence. The ribs 7', 7", 7''' are interrupted by transverse grooves 8', 8", 8''' . . . at intervals larger than the width thereof. The width of the grooves 6', 6", 6''' . . . the profile of which tapers preferably towards the bottom of the grooves, is so dimensioned that the grinding bodies cannot penetrate into them deeply enough to become jammed. Their depth amounts to more than half the width of the ribs 7', 7", 7'''', which in turn is a multiple of the width of the grooves. Each rib is shaped with a slightly cambered apex portion 9 which is followed on both sides by straight flanks 10', 10'', which end in a sharp edge confining the grooves. At the junction of the transverse grooves 8', 8", 8''' of adjacent ribs offset with respect to one another, according to the preferred modification with the longitudinal grooves, T-shaped enlargements are formed. The local reinforcements 11 provided on the longitudinal ribs 7' opposite each transverse groove impart a somewhat snake-like movement to the grinding bodies rolling down said grooves. In Figure 2, the reinforcing elements 11 appear curved with respect to longitudinal ribs 7', 7" and 7''''. However, this is an illusion created by the projection development of Figure 2, and as shown in Figure 4, the elements 11 extend straight across the rib surface.

In the plates holes 12 are provided through which extend the attachment screws. These holes form recesses on the surface of the plates, which recesses act similarly to the crossing points of the transverse and the longitudinal grooves; they are preferably arranged in line with the grooves. The screw heads are completely sunken and are thereby protected against damage by the grinding bodies.

At the left hand end of the plate, in Figure 4 a projection 13 is provided by means of which arrangement, every second groove is blocked, so that the grinding bodies are stopped before reaching the end of the plate. By this means a better distribution of the grinding bodies is attained.

The advantages of a tube mill of the type described according to the invention, are as follows:

(1) Within the mass of the grinding bodies the desirable tight packing is attained.

(2) Rolling of the grinding bodies the diameter of which corresponding approximately to the distance between the apices of two adjacent ribs, along the grooves is facilitated. The lifting effect on the grinding bodies in the circumferential sense is fully maintained.

(3) Owing to the isolation of the effective grinding surfaces from one another by the subdivision of the longitudinal ribs by the transverse grooves preferably arranged offset with respect to one another. The effect of the impact of the grinding bodies on the material to be ground is fully utilized, the cold hardening effect of the impact being localised, but also obtained in its full extent without creating flow and deformations.

(4) Due to the flat running faces formed on the ribs, the carrying-along effect in the circumferential direction is substantially independent of the diameter of the grinding bodies.

(5) Undesirable sliding of lumps of the material to be ground is blocked by the barriers which form themselves at the crossing points of the transverse longitudinal grooves.

The invention is not limited to the embodiment described hereinbefore in detail and illustrated in the drawings. Many modifications are possible without departing from the scope of the invention as defined in the appended claims. For example the invention can be applied also to mills with central discharge, having frusto-conical linings tapering from both ends of the mill towards the discharge point.

What I claim is:

1. A lining for a ball mill comprising successive frusto-conical sections narrowing in the direction of the flow of material through the mill and being separated by circular abrupt transverse steps, the lining of each of said frusto-conical sections being composed of a number of individual plates, each plate comprising a sole plate provided with a dense array of anvil means having cambered top surfaces, said anvil means being closely grouped in lines lengthwise substantially parallel with one another, transverse intervals between said anvil means preventing the entry of media, said lines in turn being disposed side by side with longitudinal intervals constituted by continuous grooves, and forming between them uniform and smooth runways for a downward rolling movement in a longitudinal direction of the media impacting on said runways.

2. A lining according to claim 1 in which the anvil means have top surfaces cambered at the apex portion followed on both sides by straight flanks which constitute the impact-receiving working surface.

3. A lining for a ball mill comprising successive frusto-conical sections narrowing in the direction of the flow of material through the mill and being separated by circular abrupt transverse steps, the lining of each of said frusto-conical sections being composed of a number of individual plates, each plate comprising a sole plate provided with a dense array of anvil means having cambered top surfaces, said anvil means being closely grouped in

lines lengthwise of the liner, substantially parallel with one another, transverse intervals between these anvil means not allowing entry of media, said lines in turn being disposed side by side with longitudinal intervals constituted by continuous grooves, said grooves and said transverse intervals between the anvils having a total depth (measured from top to bottom levels of the anvils) in excess of one half of the width of the anvil means, and the groove width being so restricted as to make them also unable to catch media, the adjacent portions of the top surfaces of anvils in adjacent lines forming uniform and smooth runways for a downward rolling movement in a longitudinal direction of the media impacting on said runways.

4. A lining according to claim 3 in which the transverse intervals between individual anvils are offset with regard to one another in adjacent lines of anvils.

5. A lining for a ball mill comprising successive frusto-conical sections narrowing in the direction of the flow of material through the mill and being separated by circular abrupt transverse steps, the lining of each of said frusto-conical sections being composed of a number of individual plates, each plate comprising a sole plate provided with a dense array of anvil means having cambered top surfaces, said anvil means being closely grouped in lines lengthwise of the liner, substantially parallel with one another, transverse intervals between them being off-

set with regard to one another in adjacent lines of anvils, and reinforcements being provided on the body of each anvil opposite the intervals on neighbouring lines for the purpose of preventing the entry of media and thereby facilitating rolling-down of media along the slopes of the liner, said lines in turn being disposed side by side with longitudinal intervals constituted by continuous grooves, also unable to catch media and forming between them uniform and smooth runways for a downward rolling movement in a longitudinal direction of the media impacting on said runways.

6. A lining according to claim 5 in which alternate grooves are blocked by projections spaced from the discharge end of the section whereby the grinding bodies are stopped before reaching the end of the plate.
